UNITED STATES PATENT OFFICE.

JOHN S. HOBBS, OF SEAFORD, DELAWARE.

COLLAPSIBLE STEP-LADDER.

No. 856,956.

Specification of Letters Patent.

Patented June 11, 1907.

Application filed May 16, 1906. Serial No. 317,176.

To all whom it may concern:

Be it known that I, JOHN S. HOBBS, a citizen of the United States, residing at Seaford, in the county of Sussex and State of Delaware, have invented new and useful improvements in Collapsible Step-Ladders, of which the following is a specification.

This invention relates to a collapsible step ladder, and the purpose of the same is to provide a step ladder wherein the parts may be readily separated and reassembled for convenience in transportation and storage, and also to render the manufacture of the same superior without in the least detracting from the necessary strength of devices of this class.

The improved step ladder embodies the same elements as usually found in the common form of step ladders with the additional structural features embodying the invention.

The invention consists in the construction and arrangement of the several parts which will be more fully hereinafter set forth.

In the drawings, Figure 1 is a perspective view of a step ladder embodying the features of the invention. Fig. 2 is a detail cross section through the upper step board and a portion of the side rails. Fig. 3 is a view similar to Fig. 2 through one of the intermediate step boards and the side rails. Fig. 4 is a rear elevation of the ladder. Fig. 5 is a detail elevation showing the step boards and rear braces of the ladder detached and the parts reduced to compact form for storage or transportation. Fig. 6 is a detail view of one of the step boards shown inverted. Fig. 7 is a side elevation of the ladder.

Similar numerals of reference are employed to indicate corresponding parts in the several views.

The numeral 1 designates side rails, 2 legs hinged thereto and adapted to be held spaced from the said rails the requisite distance by spreaders 3 formed with intermediate break joints, the spreaders being hinged to the rails 1 and having their opposite extremities free and provided with openings 5 to fit over studs or projections 6 secured to the said legs. Removably applied to the upper united extremities of the rails and legs and intermediately to the legs are a plurality of step boards 7 and 8, the top step board 7 being greater width than the intermediate step boards, as in ordinary step ladder structures.

The upper ends of the side rails 1 and the legs 2 have metallic straps 9 secured to the inner and outer surfaces thereof by suitable bolts or other preferred fastenings adapted for the purpose, said straps being preferably projected in rear of the legs on each side of the ladder and continuous for a purpose which will be more fully hereinafter set forth. The upper edge portions of the inner opposing straps form with the adjacent parts of the side rails means for receiving angular members or plates 10 secured to the top step board 7. At regular intervals on the inner opposing sides of the rails 1, angular brackets 11 are secured by suitable fastenings 12, which also engage outer metallic retaining plates 13, held in the rails and provided with central clamping bolts or other analogous fastenings 14, which extend through the brackets between the fastening devices employed for fixing the brackets and plates to the rails. The rails are longitudinally slotted, as at 15, and the clamping bolts 14 are projected through the said slots so as to avoid weakening the rail structure as much as possible by reducing the number of penetrating fastening devices. Each of the intermediate step boards 8 has a pair of angular securing members or plates 16 attached to the under side thereof close to the opposite ends, the angular portions of said members or plates depending flush with the ends of the boards and removably insertible between the angular brackets and the inner sides of the rails 1.

After the boards 8 are applied in operative position to the rails the clamping bolts 14 are tightened to securely hold the step boards in immovable relation to the rails. These clamping bolts are preferably of the thumb screw type with the thumb heads thereof located on the outer sides of the rails and pass through openings 17 in the centers of the depending portions of the angular plates secured to the step boards 8 and receiving nuts 18 on their inner ends. The top step board 7 is removably secured to the rails and legs by spring bolts 19 carried by the inner members of the straps 9 which engage the depending portions of the angular members or plates 10, suitable openings being provided in the members 8 for this purpose.

The angular members or plates on the top and intermediate step boards are firmly

braced respectively between inner portions of the straps and the rails and between the brackets on the inner sides of the rails and the ladder, and are prevented from having 5 rocking or loose movement when the spring and clamping bolts engage the same, in view of the fact that they tightly or snugly fit in the seats provided therefor between the straps and brackets and rails. This construction is also advantageous in that the 10 number of fastening devices penetrating the rails is reduced to a minimum and the step boards are free of nails or other fastenings inserted longitudinally in the ends thereof. 15 The weight imposed upon the step boards in the use of the ladder is brought to bear upon the upper ends of the rails and legs and the brackets secured to the inner sides of the rails in such manner as to produce a stable 20 ladder structure. The fastenings for the step boards are also of such simple form that said parts may be readily separated or disassociated for the purpose of transportation or storage or to reduce the latter to as small a 25 bulk as possible.

The lower extremities of the legs 2 are provided with a cross brace 19 having the ends 20 held against the edges of said legs, and also having openings 21 therein to engage 30 rearwardly projecting studs or pins 22 fixed in the legs, the ends 20 of the brace being prevented from accidentally separating from the legs by pivoted keepers 22^a of angular form which are turned thereover. These keepers 35 may be readily released from the ends of the brace and the latter withdrawn from the legs when desired to reduce the ladder to compact form. The ladder also includes in its organization auxiliary prop legs 23 connected 40 by an intermediately pivoted cross or X-brace 24, the ends 25 of the members of this cross or X-brace 24 having bearing directly against the prop legs and also provided with openings 26 to fit over pins or projections 27 fixed in the said legs, angular keepers 28 being also provided in this instance to engage 45 the ends of the members of the said brace to prevent accidental separation thereof from the prop legs. When the prop legs are not 50 in use, they are held in close relation to the rear edges of the main legs 2, and the said legs 2 have rearwardly extending guide clips 29 to prevent movement of the auxiliary prop legs. The upper ends of the prop legs 55 are hinged or pivotally disposed in the rear extremities of the straps 9. The function of these prop legs is to support the ladder in places where it is desired to firmly hold the legs 2 and rails 1 other than a horizontal support as, for instance, on stairs or analogous grades, so as to facilitate the use of the ladder in connection with a wall in a hall adjacent to a stair-way for papering, painting, or other purposes.

65 The parts of the ladder when separated, as

shown by Fig. 5, permit the rails and legs to be drawn into close relation and the step boards and braces under such conditions may also be closely packed against the folded legs and rails, and thus reduce the complete ladder 70 and allow storage thereof in a comparatively small space. This is materially advantageous in step ladders employed for domestic use. The simplicity of the several features of the ladder, and particularly the 75 fastenings for the step boards and also for the braces, render it possible to expeditiously assemble the several ladder elements when it is desired to use the ladder in operative condition. It is also proposed to apply to the ladder 80 the usual pail or bucket supporting shelf. The spreaders 3 also engage studs or projections 30 on the outer sides of the auxiliary prop legs, and adjacent to said studs or projections are pivoted keepers 31, similar to 85 those heretofore described, which are movable over the ends of the spreaders to prevent accidental disengagement thereof from the prop legs. It will be understood that the 90 prop legs are used with or independently of the main legs 2, or in most instances said prop legs will be employed in places where it is not practicable to use the main legs, and hence one set of spreaders, by the arrangement set forth, will be ample for holding both 95 the main and prop legs in proper spaced relation with respect to the rails.

While the preferred form of the ladder has been shown and described, it will be understood that modifications in the proportions, 100 dimensions and details of construction may be adopted without departing from the spirit of the invention.

Having thus described the invention, what is claimed, is:

1. In a step ladder, the combination with 105 collapsible step supporting rails and legs, of brackets immovably held against the inner sides of the legs, step boards having depending end members removably fitted between 110 the brackets and inner surfaces of the rails, the ends of the step boards being also held in close engagement with the inner surfaces of the rails when the depending members engage the brackets, and removable means engaging the rails, brackets and members.

2. A step ladder involving side rails with 115 angular brackets, clamping bolts extending through said brackets, and step boards having angular plates secured to the undersides thereof and insertible between the brackets and the rails, the clamping bolts separably engaging the said brackets and angular plates, the bolts being operative to release the angular plates without separation from 120 the ladder rails.

3. A step ladder having rails and legs, metallic straps disposed over the inner and outer sides of the rails and legs, spring bolts disposed on the inner portions of the straps, 130

- and a top step having depending members insertible between the inner straps and the adjacent ladder members, the spring bolts removably engaging the said depending member. 5
4. A step ladder having rails and legs, metallic straps engaging the upper extremities of the rails and legs, and a top step board having depending members removably insertible between the straps and the rails. 10
5. A step ladder having rails, collapsible legs movable with respect to the rails and provided with outwardly extending projections, spreaders movably attached to the rails and having openings to engage the projections on the legs, and movable keepers on a part of the legs to engage the spreaders. 15
6. A step ladder involving side rails having steps removably disposed therein, collapsible hinged legs, a lower brace removably applied at its ends to the rear edges of the legs, and keepers carried by the legs to move over the ends of the brace. 20
7. A step ladder involving side rails, independent pairs of hinged legs, removable top and intermediate step boards, the pairs of legs being hinged to move toward and from the rails and both the legs and rails being transversely collapsible when the step boards are removed, and independent brace devices removably applied to the rear edges of the pairs of legs. 25
8. A step ladder having rails with top and intermediate steps removably applied, there to, main legs hinged to move to and from the rails, auxiliary prop legs movably attached to the upper part of the ladder in rear of the main legs and movable independently of the said main legs, spreaders attached to the rails and connectible to both the main and auxiliary legs, and independent brace devices attached to the rear edges of the main legs and auxiliary legs, the rails, main legs and auxiliary legs being collapsible transversely toward each other when the steps and braces are removed. 30
9. A step ladder having rails with removable step boards, main supporting legs hingedly connected to the upper extremities of the rails, and shorter auxiliary prop legs in rear of the main legs and also hinged to the same portion of the ladder as the main legs, the rails, main legs and prop legs being unitedly collapsible in a transverse direction toward each other, the auxiliary prop legs being operative independent of the main prop legs and movable in close engagement with the latter when the main prop legs are used. 50
10. A step ladder having rails and main legs hinged thereto, step boards removably held by the rails, a brace removably engaging the lower rear edge portions of the main legs, auxiliary prop legs hinged to the same part of the ladder as the main legs, a removable collapsible cross brace engaging the rear edges of the prop legs, and spreaders movably attached to the rails for engaging both the main and prop legs, the rails and main and prop legs being collapsible. 60
11. A step ladder comprising side rails with angular brackets, step boards having angular plates secured to the underside at the ends thereof and formed with intermediate downwardly opening slots, and securing devices extending through the rails and brackets and engaging the slots of the angular plates. 70
12. A step ladder comprising side rails with angular brackets and step boards having depending end plates with intermediate slots to removably fit in the brackets, and means engaging the brackets and the slots of the plates to hold the step boards in immovable position with relation to the rails. 80
- In testimony whereof I have hereunto set my hand in presence of two subscribing witnesses.
